UNITED STATES PATENT OFFICE.

EDWARD L. FARLEY, OF JONESBORO, ARKANSAS.

COTTON CLEANER.

Application filed June 26, 1928. Serial No. 288,423.

This invention relates to a cotton cleaner, and the primary object of the same is to provide a cleaner, or rather a hull extracting cleaning feeder organization, of a comparatively simple form which may be installed without materially interfering with the setting of other equipment, or which may occupy the space now allotted to a standard upright cleaning feeder as employed by gin manufacturers, and to embody therein mechanism for directing cotton of a bolly character to a boll breaker, or receiving the cotton direct without passing it through the boll breaker to eliminate dust, dirt and trash therefrom, so that when the cotton is delivered to a distributor or emerges from the improved cleaner for further operation, as, for instance, supply to a gin stand, it will be in an advantageous condition for effective ginning and the production of a superior commercial sample grade of cotton.

A further object of the invention is to provide a cotton cleaner having therein means for preliminarily treating cotton of different grades, or for subjecting hully cotton to the action of a boll breaker, or the treatment of cotton which enters the cleaner without bolls or small portions of bolls without passing through the boll breaker, and to finally treat the cotton of either grade through the medium of a recleaning means consisting of a plurality of spiked cylinders or rollers with interfitting spike members and a lower screen, proportioned and assembled in such manner as to subject the cotton to further or recleaning treatment to materially separate dust, dirt and other foreign matter from the cotton before being delivered to a distributor, or directly to a gin stand, and to avoid deterioration or injury to the cotton treated.

A further object of the invention is to introduce between a recleaning means consisting of a series of spiked rollers located at the lower portion of the cleaner, a saw cylinder and two superposed re-cleaning spiked conveyers in advance of said cylinder and which receive the hully cotton which has been subjected to treatment by the boll breaker, the conveyers having the spikes set in spiral form in reverse position from each other and to the center, to pick the final locks of cotton from portions of hulls or other foreign matter descending to the said conveyers before the cotton thus operated upon by the saw cylinder will be subjected to

the recleaning means and delivery from the cleaner to a distributor or gin stand.

A still further object of the invention is the provision of a rotary recleaning means in a cleaner closely associated with preliminary cotton treating devices to receive bolly cotton which has been partially treated, or cotton which is of such limited bolly nature as to require only the ordinary gin stand to handle the same, and also other cotton of a higher grade and subject the same to final recleaning devices.

With these and other objects and advantages in view the invention consists in the construction and arrangement of the several parts which will be more fully hereinafter described and claimed.

In the drawings:

Figure 1 is a transverse vertical section through a cleaner embodying the features of the present invention;

Figure 2 is a section on line 2—2 of Figure 1, looking in the direction of the arrows the left-hand side only of the machine being shown; and

Figure 3 is a section on line 2—2 of Figure 1, looking in a direction opposite to the arrows, the right-hand side of the machine only being shown.

The numeral 5 designates a housing which will be constructed as an enclosure of this type and of a composite nature, or, having a frame 5^a and with partial sheet metal structures 5^b secured thereto at intervals, and which will be hereinafter specifically referred to as contributing to the formation of passages and disposition of the several parts. At the upper extremity of the housing is an inlet 6 having therebelow oppositely disposed fluted rollers 7 driven by suitable interposed mechanism from a main shaft 8 extending longitudinally through the housing and having mountings in suitable bearings. Above the rollers 7 are inwardly inclined deflection boards or chutes 7^a which direct the cotton of whatever character towards the fluted rollers 7.

A star roller 9^a having radial, triangular in cross-section, rods is mounted directly below the space between the fluted rollers 7, and below this roller 9^a, and attached to the walls of the casing, are two arcuate plates 9 which removably support the triangular in cross-section cast metal bars 9', which bars 9' operate as teeth and a grating to coact with the star roller 9^a in breaking

up the bolls and sifting the dirt therefrom, as will presently appear. The plate or valve 9^a is pivoted to assume the full and dotted line positions in Figure 1, and is provided 5 with bars 9^b similar to the bars 9', and when in full line position, these bars form a continuation with the bars 9' and cooperate with the star cylinder in assisting in breaking up the bolls before delivery to the primary 10 breaking and cleaning mechanism, the rod 9^c being manually operable and connected to the valve to cause it to assume the dotted or full line positions shown in Figure 1.

Directly below the grating 9' is a stripper 15 roller 10, the large saw cylinder 11 and a brush cylinder 12. Above and to the right of the roller 10 and cylinder 12 is an inclined deflector or chute 13, while to the right of the saw cylinder 11 and below the cylinder 20 12 is another inclined deflector 14.

A spiked boll breaker or roller 15 is mounted to the left and slightly below the star roller 9^d, and disposed in coactive relation with and to the left of the saw cylinder 25 11 are the two superposed spiked rollers 16 and 17, a screen 18 being to the left of the rollers 15 and 16 and supported in the casing. Adjacent the lower roller 17 is an inclined deflector board or chute 19 and a 30 screen 20.

The trough 21 is provided with the refuse removing screw conveyor 22, or any suitable means such as a pneumatic device.

A series of inclinedly disposed spiked cylinders 23, 24 and 25 are provided to receive the cleaned cotton from the chute 13 when the plate 9^a is in dotted line position, or from the saw cylinder 11 and brush 12, when the plate is in full line position. The convoluted screen 26 is disposed below these rollers and permits the dust and dirt to fall therethrough, but assists in conveying the cleaned cotton to the outlet end 27. This outlet end is provided with the manually controlled valve 30, while disposed adjacent to the spiked roller 25 is a valve 28. A door 29 is provided for access in cleaning and repairing. Other doors may be disposed throughout, as may be found necessary.

50 The present cleaner is adapted to be supported from the usual gin stand, the top end 31 of which is illustrated.

From the foregoing description, it is evident that the star roller 9^d will cooperate 55 with the grating 9' to assist in breaking up the bolls as the same are delivered through the fluted rollers 7. Should the valve 9^a be in the full line position, the cotton bolls will be broken and delivered to the spiked wheel 60 15, which, in turn, will deliver them to the spiked wheel 10 and the saw cylinder 11 which, cooperating with the two spiked wheels 16 and 17, will finally cause the breaking up of the bolls and the proper cleaning of the cotton therefrom, the refuse

falling to the lower portion of the cleaner to be carried away by the rotating screw 22. Thus the cleaned cotton will be delivered by the saw cylinder 11, the spiked roller 10 and the brush cylinder 12 to the inclined chute 70 14 and thence, by means of the re-cleaning spiked rollers 23, 24 and 25, to the outlet 27.

Where it is unnecessary to break the bolls, the valve 9^a is moved to the dotted line position in Figure 1 so that the cotton is delivered directly from the star roller 9^d and the grated bars 9' over the deflector or chute 13 directly to the spiked rollers 23, 24 and 25.

As shown in Figure 2, it will be noted that the spikes on the roller 16 are arranged 80 spirally from the center toward the ends so that the material is conveyed from the ends toward the center, whereas the spikes on the roller 17 are arranged spirally to convey from the center toward the ends. It will 85 also be noted that the screen 20 terminates to provide a space for permitting the hulls to fall through to the outlet 21.

It will also be noted that an air-controlling shutter or valve 33 is provided at the top of 90 the casing above the rollers 15, and with the valve 28 the proper air control is provided for the present cleaning apparatus.

What is claimed is:

1. A cotton cleaner of the class specified 95 comprising a housing having an upper inlet and a side outlet, deflecting means including a manually operable valve adjacent the inlet to cause the cotton to be directed in either one of two directions, a grating co-operating therewith, a star roller cooperating with the grating, a boll-breaker within the housing at the side thereof opposite to the outlet and to receive the cotton and bolls from the star roller and grating, a cleaning means cooperating with the boll breaker, and a plurality of re-cleaning devices to receive the cotton either from the first means or directly from the valve and star roller and positioned to direct the cotton through the side 100 outlet.

2. A cotton cleaner of the class specified comprising a housing having an upper inlet and side outlet, two fluted rollers disposed adjacent the inlet, a star roller below and between the fluted rollers, a fixed arcuate grating disposed below and in coactive relation with the star roller, a valve adapted to coact with the grating or to open directly to the outlet, boll breaking mechanism mounted at the opposite side to the outlet and valve for receiving the cotton and bolls from the fluted roller and grating, a cleaning mechanism disposed below the fluted roller and grating and disposed to receive the cotton and bolls from the boll breakers, and a plurality of re-cleaning spiked rollers disposed to receive the cotton from the first 115 cleaning device for delivery through the side outlet or to receive the cotton directly 120 125 130

from the star roller when the valve is open.

3. A cotton cleaner of the class specified comprising a housing having an upper inlet and side outlet, two fluted rollers disposed adjacent the inlet, a star roller below and between the fluted rollers, a fixed arcuate grating disposed below and in coactive relation with the star roller, a valve adapted to coact with the grating or to open directly to the outlet, boll breaking mechanism mounted at the opposite side to the outlet and valve for receiving the cotton and bolls from the fluted roller and grating, a cleaning mecha-

nism disposed below the fluted roller and grating and disposed to receive the cotton and bolls from the boll breakers, a plurality of re-cleaning spiked rollers disposed to receive the cotton from the first cleaning device for delivery through the side outlet or to receive the cotton directly from the star roller when the valve is open, said first cleaning mechanism including superposed spiked and saw cylinders and a brush cylinder.

In testimony whereof I have hereunto set my hand.

EDWARD L. FARLEY.
